BAFFLE SYSTEM FOR STIRLING BOILERS.

1,132,013.

Specification of Letters Patent.

Patented Mar. 16, 1915.

Application filed July 5, 1913. Serial No. 777,503.

To all whom it may concern:

Be it known that I, DAVID S. JACOBUS, a citizen of the United States, residing at Jersey City, in the county of Hudson and 5 State of New Jersey, have invented certain new and useful Improvements in Baffle Systems for Stirling Boilers, of which the following is a specification.

My invention relates to a system of special baffles for Stirling boilers, and will be 10 understood by reference to the accompanying drawings in which—

Figure 1 is a side elevation, partly in section, of one embodiment of my invention; 15 and Fig. 2, a similar view of another embodiment.

Similar reference numerals indicate similar parts in the several views.

The present invention is applicable to a 20 Stirling boiler with two upper steam and water drums and one mud drum, as well as one having three steam and water drums and one or two mud drums.

In the forms shown, the numeral 1 designates the walls of the boiler setting; 2 the 25 furnace having in Fig. 1 a chain grate stoker 3, and in Fig. 2 a Roney stoker; 4, 5 and 6 banks of generating tubes expanded at their lower ends into a mud drum 7 and 30 at their upper ends into steam and water drums 8, 9 and 10 respectively. These latter drums are connected by water circulators 11 and 11', and steam circulators 12 and 12'. Coverings of fire bricks 13 resting on 35 the water circulating tubes prevent the gases passing above these tubes. A steam main 14 leads from the central drum 9 to the cross box 15 of a superheater placed in the space between the first and second banks of tubes.

In the standard Stirling boiler a baffle rests 40 against the rear tubes of the first bank reaching from the mud drum nearly to the top of the bank, and a second baffle rests against the rear tubes of the second bank, 45 reaching from the center steam and water drum nearly to the bottom of the bank, these two baffles guiding the gases up the first bank of tubes, down the middle bank, and up the rear bank to the outlet flue. To increase 50 the heat transfer rate and the efficiency of the boiler, I have provided the following described systems of baffling whereby the gases are made to first pass over the upper part of the first bank of 55 tubes and then to flow over the lower part

of the first bank at the back of a vertical wall at the rear of the furnace, the space at the back of the wall forming a dust pocket which is useful in collecting the dust deposited from the gases.

With most forms of furnaces for Stirling boilers a fire brick arch is sprung immediately in front of the first bank of tubes. Such arches are, however, difficult to maintain, as they are exposed to the high temperature of the furnace. In the present construction they are dispensed with thus leading to economy by eliminating the cost of maintenance, and, at the same time, permitting an arrangement of baffles whereby the portion of the boiler tubes acted upon by the direct radiant heat of the fire may be at a greater distance from the fire than in the usual form of setting.

Referring to Fig. 1 the furnace shown has 75 an ignition arch 16, and a bridge wall 17 supporting a water box 18, the latter overhanging the rear of the stoker. Supported by the water box, and by brick work built over from the bridge wall, is a vertical wall 80 19 extending upwardly to the front row of the first bank of tubes, and from one side wall of the setting to the other side wall. From the top of wall 19 a baffle 20 is run across the bank 4, and from the top of this 85 baffle an inclined baffle 21 is laid on top of the bank, said last-named baffle reaching to nearly the top of the bank so as to permit a full sweep of the gases across the upper end of the tubes into the secondary combustion chamber formed between the first and second banks of tubes. The baffles 20 and 21 form, in reality, a continuation of wall 19 to separate the first bank into upper and lower portions, causing the gases to 90 first pass over the upper portion and then over the lower portion at the rear of wall 19. To cause the gases to flow downwardly among the tubes of the middle or second bank, and to cross and recross the lower portion of the tubes of the first bank, I introduce the baffle 22 and the cross baffle 23, the baffle 22 being a baffle found in the standard Stirling design. The rear bank of tubes is shown without cross baffles although the 95 same may be used. In the absence of cross baffles, I prefer to introduce the usual shelf 100 extending from the rear wall of the setting to the tubes of the rear bank.

As indicated by the arrows, the gases 110

from the furnace are first directed along and across the tubes of the first bank upon the furnace side of wall 19; thence into the superheater space and downwardly along 5 the tubes of the second bank; then across the tubes of the first bank below baffle 20 and at the rear of wall 19; and are then compelled to recross the lower ends of the tubes of the first bank and to cross the lower 10 ends of the tubes of the second bank; and then upwardly along the tubes of the rear bank to the stack outlet 25.

As shown in the drawing the top of the wall 19 is a little below the center of the tube 15 length although this exact location of the wall is not material, the essential feature being that the wall shall be so located as to provide a space at the rear thereof to form a dust pocket and to render the lower part of 20 the first bank of tubes effective, and thereby increase the efficiency. In addition to this the following advantages may be named.

The portion of the boiler tubes acted upon by the direct radiant heat of the fire is at a 25 greater distance from the fire than in most settings, and the trouble often experienced through blistering of the tubes will be minimized. Moreover a furnace is provided in 30 which heat is reflected from hot brick work on all sides, thus assisting the combustion and minimizing smoke. In order that the tubes shall be at the proper distance from the surface of the fire with ordinary furnace arrangements, it is often necessary to raise 35 the boiler to a relatively high elevation, thus increasing the cost of the suspensions and of the brick work. The secondary combustion chamber between the first and second banks of tubes is also of great advantage 40 in reducing smoke and giving increased efficiency.

In the above described construction there is a saving in many cases as the boiler can be set low with respect to the stoker.

45 The above described furnace arrangement is applicable to hand firing as well as to all forms of stokers, and the baffling shown in Fig. 1 is susceptible of modification, one such modification being shown in Fig. 2. 50 In this embodiment of my invention the vertical wall 26 rests upon the bridge wall 27 and extends upwardly to the first bank of tubes as in Fig. 1. From the top of the vertical wall 26 a short inclined baffle 28 is supported upon the front row of tubes of the first bank, and from the end of this short baffle a baffle 29 is run across the first bank of tubes, permitting, as in Fig. 1, a full sweep 55 of the gases across the top of the bank. The baffles 28 and 29 form, in reality, a continuation of wall 26 for the same purpose as described in connection with the wall and baffles of Fig. 1. In some cases the cross baffle 29 would be omitted and the baffle 28 60 preferably extended further upward than

shown. Instead of the usual baffle resting on the second bank, I have, in Fig. 2, shown a baffle 30 resting upon the front tubes of the second bank and reaching from the middle drum 9 downwardly, and a second baffle 70 31 resting upon the rear tubes of the second bank and reaching from the mud drum 7 upwardly. A cross baffle 32 in some cases is made to extend from the end of baffle 30 across the space between the first and second banks for deflecting the gases into the lower part of the first bank. To cause the gases to cross and recross the tubes of the rear bank, I introduce cross baffles 33, extending laterally from baffle 31, and shelves or baffles 34 80 extending from the rear wall of the setting, the gases in this arrangement, after leaving the first bank, pass upwardly along the tubes of the second bank, and then downwardly across and among the tubes of the rear bank 85 to the stack outlet 35.

By discharging the gases at a low point in the setting advantages may be gained where an economizer is attached to the boiler. The outlet may be in the rear wall of the setting in place of in the floor of the setting. Another advantage secured through a downward flow of the gases over the third bank 90 of tubes with cross baffles, is that less soot or ashes will lodge in the cross baffles than will an upward flow of the gases, and in dusting the exterior of the boiler by means of a steam or air lance the dust will be more easily displaced as it will naturally be carried more readily downward by the flow of 100 the gases than it will be carried upward.

By providing a space between the rear of the vertical wall and the boiler tubes, any dust deposited from the gases at this point can be allowed to fall into a pocket from 105 whence it can be readily removed. The form of this dust pocket is immaterial, a wide mouthed pocket 36 being shown in Fig. 2, whereas in Fig. 1 the dust pocket 37 is contracted at the top. In some instances this 110 dust pocket may not extend down as far as the floor level, as for example, in Fig. 1 the pocket may come at approximately the level of the middle of the mud drum 7, or it may be at any other desired height. 115

The construction above described includes a wall at the rear of the furnace chamber which causes the gases to first pass over the upper part of the first bank of tubes, that is, the gases are caused to travel over the lower 120 part of the first bank of tubes at the rear of the wall after they have traveled over the upper part of the bank. It is not necessary, however, that the gases enter at the top of the first bank. In addition to the baffles 21 125 and 22 shown in Fig. 1 on the first bank, there may be an additional baffle, supported by the front tubes of the first bank, extending downwardly from drum 8 a sufficient distance toward the top of wall 19 so as to 130

cause the gases to enter at the middle part of the bank and to then flow upwardly over the upper part of the bank, and after this to flow over the lower part of the first bank of 5 tubes.

The baffle 20 crossing the first bank of tubes, shown in Fig. 1, and baffle 29 in Fig. 2, may be built up of a cast iron backing with the front side protected by tiling, or by 10 means of a material introduced in a plastic condition which afterward dries out and becomes hard. The same construction may be used for the baffles 23 in Fig. 1 and 32 in Fig. 2.

15 What I claim and desire to secure by Letters Patent of the United States is:—

1. A boiler of the class described having a plurality of banks of tubes, a furnace, a secondary combustion chamber between the 20 first and second banks of tubes, a wall at the rear of the furnace chamber extending upward in front of the first bank, and a baffle extending parallel with the tubes to a point above the midlength of the tubes and supported upon the tubes of the first bank, whereby the gases are caused to first enter said bank at the upper part thereof and to cross into said secondary combustion chamber, substantially as described.

2. A boiler of the class described having a plurality of banks of tubes, a furnace, a secondary combustion chamber between the first and second banks of tubes, a wall at the rear of the furnace chamber extending upward 35 in front of the first bank, a baffle extending parallel with the tubes to a point above the midlength of the tubes and supported upon the tubes of the first bank, whereby the gases are caused to first enter said bank at the upper part thereof and to cross into said secondary combustion chamber, and a downward extending baffle at the rear of the second bank.

3. A boiler of the class described having a 45 plurality of banks of tubes, a furnace, a secondary combustion chamber between the first and second banks of tubes, a substantially vertical wall at the back of the furnace chamber and extending upward in front of the first bank, a baffle extending parallel with the tubes and supported upon tubes of the first bank near the front of said bank, whereby the gases are caused to first cross the first bank at the upper part thereof and 55 enter said secondary combustion chamber, and a cross baffle at the lower part of the first bank to cause the gases to enter the lower part of said bank from the secondary combustion chamber, substantially as described.

4. A boiler of the class described having a 60 plurality of banks of tubes, a furnace, a secondary combustion chamber between the first and second banks of tubes, a substantially vertical wall at the back of the furnace

chamber and extending upward in front of the first bank, a baffle extending parallel with the tubes and supported upon tubes of the first bank near the front thereof, whereby the gases are caused to first cross the first bank at the upper part thereof and enter said secondary combustion chamber, and a superheater in said secondary combustion chamber, substantially as described.

5. A boiler of the serial multiple bank class described having a substantially vertical wall at the back of the furnace chamber and extending upward in front of the first bank, a secondary combustion chamber between the first and second banks of tubes, 70 and a baffle forming an extension of the wall to cause the gases to flow across the upper part of the first bank directly into said secondary combustion chamber, substantially as described.

6. A boiler of the serial multiple bank class described having a substantially vertical wall at the back of the furnace chamber and extending upward in front of the first bank, a secondary combustion chamber between the first and second banks of tubes, a baffle forming an extension of the wall for causing the gases to flow across the upper part of the first bank directly into said secondary combustion chamber, and a superheater in said secondary combustion chamber, substantially as described.

7. A boiler of the class described having a plurality of banks of tubes, a furnace, a substantially vertical wall at the back of the 10 furnace chamber and extending upward in front of the first bank, a baffle extending parallel with the tubes and supported upon tubes of the first bank near the front thereof, whereby the gases are caused to first cross the first bank of tubes at the upper part thereof and enter a secondary combustion chamber at the rear of said bank, a dust pocket at the rear of said wall, and a cross baffle at the lower part of the first bank of tubes to cause the gases to enter the lower part of said bank and to direct any dust in the gases into said pocket, substantially as described.

8. A boiler of the class described comprising a plurality of banks of tubes, a wall at the rear of the furnace chamber to cause the gases to first pass over the upper part of the first bank of tubes, and a baffle to cause the gases to then flow across and over the tubes at the lower part of the first bank at the rear of said wall and to recross the same tubes in the opposite direction, and thence to the second bank of tubes.

9. A boiler of the class described, containing a plurality of banks of tubes extending upward from a mud drum, a wall in front of the mud drum and between it and the furnace chamber, said wall extending upward leaving a dust-collecting pocket at 130

the rear thereof, and baffles to cause the gases to flow across the upper portion of the first bank of tubes in a secondary combustion chamber between the first and second banks of tubes, and then downward to direct any dust in the gases into said pocket, substantially as described.

10. A boiler of the class described comprising three banks of tubes, a wall at the rear of the furnace chamber to cause the gases to first pass over the upper part of the first bank of tubes, and baffles to cause the gases to then pass over the lower portion of the first bank of tubes, thence upward over the tubes of the second bank, and finally downward over the tubes of the third bank.

11. A boiler of the class described comprising three banks of tubes, a wall at the rear of the furnace chamber to cause the gases to first pass over the upper part of the first bank of tubes, baffles to cause the gases to then pass over the lower portion of the first bank of tubes, thence upward over the tubes of the second bank, and cross baffles in the third bank of tubes to cause the gases to cross and recross the tubes as they travel downwardly over the last-named bank.

12. A boiler of the class described comprising a plurality of banks of tubes, steam and water and mud drums into which said tubes are expanded, a wall at the rear of the furnace chamber extending upwardly to the first bank, a baffle upon the front row of tubes of the second bank and reaching from the middle drum downwardly and a cross baffle extending therefrom among the tubes of the first bank at the rear of said wall, a second baffle resting upon the second bank and reaching from the mud drum upwardly, whereby the gases are caused to first pass over the upper portion of the first bank, then over the lower portion of the first bank at the rear of said wall, thence upwardly over the tubes of the middle bank, and thence downwardly over the tubes of the rear bank.

13. A boiler of the class described, comprising three banks of tubes, steam and water drums and a mud drum into which the tubes are expanded, a wall at the rear of the furnace chamber and a baffle to cause the gases to pass over the upper part of the first bank, and baffles to cause the gases to flow downward after crossing the upper part of the first bank, then upward over the tubes of the second bank, and then down-

ward over the tubes of the third bank, substantially as described.

60

14. A boiler of the class described, comprising three banks of tubes, steam and water drums and a mud drum into which the tubes are expanded, a wall at the rear of the furnace chamber, a baffle supported on a row of tubes of the first bank to cause the gases to cross the first bank at the upper part thereof, and baffles to cause the gases to flow downward after crossing the upper part of the first bank, then upward over the tubes of the second bank, and then downward over the tubes of the third bank, substantially as described.

65

15. A boiler of the class described, comprising a plurality of banks of tubes, steam and water drums and a mud drum into which the tubes are expanded, a wall at the rear of the furnace chamber and a baffle to cause the gases to pass over the upper part of the first bank, a baffle extending along the front of the second bank from the upper end thereof and terminating short of the lower end, and a baffle extending along the rear of the second bank from the lower end thereof and terminating short of the upper end, substantially as described.

75

16. A boiler of the class described, comprising a plurality of banks of tubes, steam and water drums and a mud drum into which the tubes are expanded, a wall at the rear of the furnace chamber extending upward to the first bank, a baffle supported upon the tubes of the first bank, a baffle extending along the second bank from the upper end thereof and terminating short of the lower end, and a cross baffle in the lower part of the space between the first and second banks of tubes, for the purpose described.

80

17. A boiler of the class described comprising a plurality of banks of tubes, steam and water drums and a mud drum into which the tubes are expanded, baffles to define the path followed by the gases in passing from one bank to the next and to cause the gases to enter the last bank at the upper part thereof and flow downward among the tubes of said bank to the lower part thereof.
